UNITED STATES PATENT OFFICE.

JOHN F. CRAIG, OF FAIRMONT, WEST VIRGINIA, ASSIGNOR TO MONONGAH GLASS COMPANY, OF FAIRMONT, WEST VIRGINIA, A CORPORATION OF WEST VIRGINIA.

DESIGN FOR A GOBLET.

Application filed April 8, 1926. Serial No. 17,218. Term of patent 7 years.

To all whom it may concern:

Be it known that I, JOHN F. CRAIG, a citizen of the United States, residing at 1101 Virginia Avenue, Fairmont, in the county of Marion and State of West Virginia, have invented a new, original, and ornamental Design for Goblets, of which the following is a specification, reference being had to

the accompanying drawing, forming part thereof.

The figure is a plan view of a goblet showing my new design.

I claim:—

The ornamental design for a goblet, as shown.

JOHN F. CRAIG.
